UNITED STATES PATENT OFFICE

WILLIAM J. DAVEY, OF TAKOMA PARK, MARYLAND

WALL AND CEILING STRUCTURE

Application filed February 18, 1931. Serial No. 510,746.

The present invention relates to improvements in the construction of walls and ceilings for theaters, auditoriums, halls and the like, and the primary object of the invention is to provide a wall structure for the treatment of acoustics.

A further object is to provide a wall structure which will be highly absorbent to sound waves for preventing undesirable reverberation, and possessing characteristics affording a desired amount of resonant quality to the wall.

A further object is to provide an acoustic wall structure which may be economically manufactured, is non-inflammable, and which may either be applied as a coating directly to the wall or moulded into blocks or slabs of suitable shape and size for application to the wall.

20 A further object of the invention resides in the provision of an acoustic wall structure composed of a plastic material of such nature as to provide inter-communicating voids or interstices opening at the face or exposed surface of the wall and having embedded in isolated relation therein, elastic bodies providing spaced apart vibratory or resonant sections having irregular channels therethru between the elastic bodies and wall surface.

30 A further object is to provide a porous wall structure having porous vibratory sections for affording some resonant quality to the wall, with damping means for the vibratory sections.

35 Other objects and advantages of the invention will be apparent from the following detailed description, taken in connection with the accompanying drawing forming a part of this specification and in which drawing:

Figure 1 is a plan view of a block or slab formed in accordance with this invention.

40 Figure 2 is an enlarged fragmentary sectional view of a wall embodying the features 45 of this invention and showing the porous

formation of the acoustical material providing the open voids or interstices.

Figures 3 and 4 are sectional views on the respective lines in Figure 1 and showing the position of the elastic damping pad within the body material of the block or slab, without showing in detail the open voids or interstices between the granules of the body material as disclosed clearly in Figure 2.

Referring to the drawing in detail and wherein similar reference characters designate corresponding parts thruout the several views, the letter A designates an acoustic wall block or slab constructed in accordance with this invention and B a base wall structure which in the example shown is of solid masonry construction; such types of walls being non-absorbent and practically impervious to sound waves.

The wall slab A may be moulded in any desirable shape and size found most suitable and is formed of the plastic body material 5 in which is embedded an elastic body 6 having its margins spaced wholly inwardly of the surfaces of the slab.

70 While the composition of the absorbent body material 5 may be varied to a certain extent, a structure possessing the desired characteristics has been obtained in the following manner:—Granular material such as crushed brick, oyster shell, coke or slag of a size to pass thru a number eight mesh screen, fifty per cent by volume; plaster of Paris or any gypsum plaster, twenty-five per cent by volume; and water twenty-five per cent by volume. A small quantity of some retarder such as carpenters' glue may be added to this mixture, the quantity depending upon conditions at the time of mixing. A body material so formed may either be

80 applied directly to a base wall structure or moulded into suitably shaped blocks or slabs having an approximate thickness of one inch and then applied to the wall as by a suitable 85 binding material as shown at 8 in Figure 2. 90

The specific proportions may be varied slightly and in some instances it may be found desirable to use a mixture of two or more of the granular materials.

Referring to Figure 2, a body material 5 so formed will provide irregular inter-communicating voids or interstices 10 about the granules of the body material so that the block or slab A is rendered very porous and highly absorbent to sound waves. These voids or interstices 10 extend to and open at the face or exposed surface of the block and the formation of the voids is due to the small quantity of water used in the mixing and also the small quantity of binder used which serves to bind the granular particles together at their points of contact without being of sufficient quantity to completely fill the spaces between the particles. The porosity of the blocks when applied to a wall will provide a wall facing which will be highly absorbent to sound waves and thereby preventing undesirable reverberation.

Embedded in the porous body material 5 is the elastic body 6 which may be in the form of a thin sponge rubber pad spaced below the face side or exposed surface of the wall block and providing a vibratory or resonant section 20 having its margins spaced inward from the marginal edges of the block as shown by dotted lines in Figure 1. As will be seen in Figure 2, the voids 10 extend thru the vibratory section 20 from the pad 6 to the surface of the block so that a porous section of a vibratory character is formed over the yieldable pad for affording some resonant quality to the wall. This cellular pad 6 aside from adding to the sound absorbing quality of the block, acts as a cushioning element for damping the vibrations of the porous vibratory section 20 whereby an excessive amount of sound reflection is eliminated.

When the blocks or tiles are applied as a facing to a base wall construction, a wall structure having a high degree of sound absorption will be formed, provided with isolated damped vibratory sections affording some resonance quality to the wall. When the body material 5 is applied directly to the base wall construction, the pads 6 are embedded in the material at about one quarter of an inch below the surface thereof and in spaced relation to one another so as to provide isolated damped vibratory sections over the entire wall surface.

In place of the sponge rubber pads for damping vibrations of the vibratory sections 20, I may use sheets of corrugated material or any other sheet like material of a porous yieldable character capable of providing a cushioning effect upon the vibratory sections. While the elastic pads 6 have been shown of rectangular shape it is to be under-

stood that these pads may be of various other shapes.

From the foregoing it will be apparent that an improved construction for wall and ceiling structures has been provided for the treatment of acoustics, possessing marked qualities of sound absorption and embodying damped vibratory sections for affording some resonant qualities to the wall.

Changes in detail may be made to the form of invention herein shown and described without departing from the spirit of the invention or the scope of the following claims.

I claim:

1. A wall or ceiling structure embodying a coat of porous material formed with isolated vibratory sections on its surface, and damping means for the vibratory sections.

2. A wall or ceiling structure embodying a coat of porous material formed with isolated porous vibratory sections on its surface, and damping means for the vibratory sections.

3. A wall structure comprising a coat of porous sound absorbing body material, and elastic bodies embedded in isolated relation in the body material.

4. A wall structure comprising a coat of porous sound absorbing body material, and cellular pads of yieldable nature embedded in isolated relation in the body material providing vibratory body material sections spaced apart over the surface of the wall.

5. A wall structure comprising a porous body material having voids opening at the face of the wall, and elastic pads embedded in isolated relation in the material parallel to the face of the wall.

6. A wall structure comprising a coating of plastic body material having open voids opening at the exposed face of the wall, and sponge rubber pads embedded in isolated relation in the body material.

7. A wall structure for the treatment of acoustics comprising a coating of plastic body material, and a plurality of flat yieldable pads embedded in isolated relation in the body material in a plane parallel to the face of the wall.

8. An acoustical wall structure comprising a coat of body material, and yieldable pads embedded in the material in spaced apart relation providing separate vibratory sections, said vibratory sections having voids opening at the face of the wall.

9. A wall comprising a solid base wall structure of poor acoustic qualities, a coating of body material applied to the base wall embodying open bonded granules, and elastic pads embedded in isolated relation in the body material between the inner and exposed surfaces of the material.

10. An acoustical wall block composed of a plastic body material, and an elastic pad

embedded in the material parallel to the face of the block.

5 11. An acoustical wall block comprising a porous body portion having sound absorbing qualities, and a cellular pad of a yieldable character embedded in the body portion parallel to the face of the block.

10 12. An acoustical wall block comprising a body portion moulded from openly bonded granules, and a pad of a yieldable nature embedded in the body portion parallel to the face of the block.

15 13. An acoustical wall block comprising a porous body portion, and a sponge rubber pad embedded in the material of the body portion with its margins spaced inwardly from the margins of the block.
